UNITED STATES PATENT OFFICE.

ERNST LAUSCHKE, OF CHICAGO, ILLINOIS, ASSIGNOR TO BARNHART BROS.
& SPINDLER, OF SAME PLACE.

DESIGN FOR TYPE.

SPECIFICATION forming part of Design No. 18,969, dated March 19, 1889.
Application filed January 26, 1889. Serial No. 297,726. Term of patent 14 years.

To all whom it may concern:

Be it known that I, ERNST LAUSCHKE, a subject of the Emperor of Germany, residing at Chicago, county of Cook, and State of Illinois, have invented a new and original Design for a Font of Printing-Type, of which the following is a specification, reference being had to the accompanying typographical impressions, forming a part thereof.

- 10 This design consists of upper and lower case letters, upper-case or large-size figures, points, dollar-mark, character &, and two or 15 naments. Its general characteristic is the grotesque and freakish irregularity of all the lines, which particularly consists in making all the upright strokes irregularly tapering from one end to the other and irregularly swelled at the larger end, but terminating abruptly—that is, without curvature—at the tip 20 of such swelled end. This feature is illustrated in nearly all the vertical strokes of both upper and lower case letters, as lower-case b, d, h, i, k, l, p, q, r, and t, and in the exclamation-point, and figures 1, 4, and 7, and 25 upper-case letters A, B, D, F, H, I, J, K, L, M, N, P, R, T, V, W, X, and Y. An analogous characteristic is the similar taper and irregularly but abruptly swelling termination of certain lines, as the oval of lower-case letters 30 a, b, c, d, e, p, and q and upper-case letters B, C, D, E, G, P, R, and S. The irregular and freakish character of the lines is further marked in the principal strokes or stems of upper-case A, B, and M, which, in addition to being 35 irregularly tapered, as already described with respect to some such strokes, have a prominent irregularity or swell about half-way between the final swell and the middle point of the stroke, whence it diminishes quite abruptly and continues comparatively light to 40 the finish. A characteristic analogous to this last is observable in the vertical stroke of lower-case b, in the middle stroke of capital M, in the final stroke of capital N, and the 45 stem of capital R, wherein a slight enlarge-

ment occurs about midway in the entire length of said strokes, respectively, except in the instance of lower-case b, where the enlargement occurs immediately opposite the upper expanded end of the oval.

Another characteristic, tending to produce the grotesque appearance which marks the design, is exhibited in the ovals of lower-case b, d, p, and q, which are disjoined from their stems at the swelled or enlarged end of the oval where they would ordinarily join, and at the other end reverse their curvature, so as to be very slightly concave outward, making their acute angle with the stem on the inside of the oval. The same characteristic appears 55 in the ovals of capitals B, D, P, and R. A like characteristic is noticeable in lower-case h and in the form of the second element of lower-case m and n. In addition to these characteristics the principal elements of capitals A, H, V, and all four elements of capital W are bent convex outward.

I claim—

The design for a font of printing-type herein shown and described, wherein letters have 70 irregularly grotesque or freakish forms characterized by the irregular tapering of the lines and terminating the same with abrupt enlargements in some lines, as of capitals A, B, and M, and by reversing the curvature of 75 the ovals of such letters as lower-case b, d, t, and q and upper-case B, D, P, and R at the junction of such ovals with the stems, causing them to make acute angles with the stems on the inside of the ovals, and by irregularly 80 bending the principal strokes or stems of some capitals, as A and H, substantially as set forth.

In testimony whereof I have set my hand, at Chicago, Illinois, this 12th day of January, 85 1889.

ERNST LAUSCHKE.
